UNITED STATES PATENT OFFICE.

GEORGE EUGENE MITTINGER, OF YOUNGSTOWN, OHIO.

BARREL OR KEG.

Application filed March 29, 1922. Serial No. 547,682.

To all whom it may concern:

Be it known that I, GEORGE E. MITTINGER, a citizen of the United States, residing at Youngstown, in the county of Mahoning and 5 State of Ohio, have invented certain new and useful Improvements in Barrels or Kegs, of which the following is a specification, reference being had therein to the accompanying drawing.

- 10 This invention relates to improvements in barrels or kegs, and more particularly to improvements in metallic collapsible barrels or kegs having a novel construction, whereby the barrel is held together in its assembled 15 form, being also constructed in such a manner that the unassembled parts of the barrel will stack or nest so that in shipment tonnage can be packed in a freight car or the like.
- 20 The object of my invention is to provide a collapsible barrel or keg made in a plurality of sections and adapted to be readily collapsed and assembled as desired.

Another object of my invention is to provide a barrel or keg made in a plurality of sections and adapted to be collapsed so that the sections can be readily nested or stacked, whereby a vast amount of space is saved in the transportation of the empty containers and tonnage can be packed in a freight car or the like.

A further object of my invention is to provide a collapsible container having a novel means for holding it in assembled 35 form.

A still further object of my invention is to provide a collapsible container in which the heads are readily, securely and easily fastened upon the barrel sections to close them and thereby strengthens and more securely locks the barrel sections together and prevents them from collapsing.

Another and further object of my invention is to provide a container of this character, which is cheap and simple of manufacture, highly efficient in use and having certain novel details of structure which will hereinafter be more fully described.

In the drawings:

- 50 Figure 1 is a fragmentary view in front elevation of a barrel constructed in accordance with my improved invention, a portion of the barrel being shown in longitudinal vertical section.

Fig. 2 is a fragmentary top plan view of 55 my improved barrel with the barrel head in place.

Fig. 3 is a fragmentary longitudinal vertical sectional view on the barrel heads in 60 stacked or nested relation.

Fig. 4 is a fragmentary view in transverse section showing the barrel section locking or fastening means.

Fig. 5 is a fragmentary view in front elevation of a modified form of my improved 65 barrel construction, a portion of the figure being shown in longitudinal vertical section.

Fig. 6 is a fragmentary perspective view of the barrel and barrel head as shown in 70 Fig. 5, a portion of the figure being shown in longitudinal vertical section.

Fig. 7 is a fragmentary longitudinal vertical sectional view of the barrel heads used 75 in a modified form, the same being shown in stacked or nested relation.

Fig. 8 is a fragmentary longitudinal vertical sectional view of the barrel sections in stacked or nested relation.

In the drawings in which like parts are 80 designated by similar reference numerals, A represents one of the barrel sections, and B represents the other barrel section, these sections being each of a semi-circular shape in cross-section and elongated, as clearly appears in the drawing, and when in their assembled position constitute a round hollow cylinder having open ends.

Although I have shown and described the 90 barrel body as being composed of two sections, it will be readily understood that the body may be made in as many sections as desired, without departing from the spirit of my invention.

Each of the semi-circular barrel sections A 95 and B are provided at their opposite longitudinal edges with an outwardly rolled portion 9, and an inwardly rolled portion 10, which extend the entire length or depth of the barrel, the ends of the rolled portions 100 terminating at an outwardly rolled bead or chime 11, at each end of the barrel sections, the said chimes being of approximately U-shape having an upwardly extending vertical surrounding wall 12, which is the end 105 proper of the barrel sections.

These rolled portions 9 and 10 are composed of a double thickness of the material

from which the sections are constructed, the barrel material being bent backwardly upon itself as at 11, to provide for this reinforcement.

- 5 As will be readily understood, these barrel sections have an inward roll on one edge and an outward roll at its opposite edge. In assembling the barrel sections the inwardly rolled edge of one barrel section interlocks 10 with the outwardly rolled edge of the other barrel section. These rolls are constructed in such a manner that the rolled edges of the two barrel sections A and B will slide longitudinally or in a telescoping manner, 15 one into the other. To provide for this sliding, the ends of the rolls 9 and 10 are curved or hooked as at 13 and 14, and this construction further prevents the barrel sections from being pulled apart laterally.
- 20 I have provided the barrel heads C for closing the ends of the barrel sections A and B, and these heads C are composed of a bottom 15, which is slightly convex, as at 16, to strengthen it. Surrounding the bottom 25 15 of the heads are the upwardly extending sides 17, which have an upward taper or slant as shown. The upper ends of the sides 17 of the barrel heads terminate in a horizontal flange or edge 18, from which extend 30 at a plurality of points tongues 19, of a length a little greater than the depth of the heads.

When the sections A and B of the barrel are in their assembled position or form, as 35 shown in Fig. 1 of the drawings, the heads C are dropped into the ends of the cylinder formed by the sections, the peripheral flange 18 resting upon the vertical end 12 and thereby supporting the head in place. To 40 lock the heads in position to close the container, the tongues 19 are bent downwardly and inserted in the openings 21, which are provided in the upper face of the U-shaped bead or chime 11. As these tongues 19 are 45 of a length greater than the distance from the top edge of the barrel sections to the bottom inner wall of the chimes, these tongues will curl outwardly and upon themselves, as at 22, when the ends of the tongues 50 strike the bottom of the chimes. This curling or rolling effect of the tongues is as- 55 sured by the fact that the openings 21 in the chimes are so positioned that when the tongues are inserted through them, they will 60 strike the outward flare of the bottom wall of the chime and as they are forced downwardly will follow and assume the U-shape of the chime. By this construction, the heads are locked securely in the barrel in 65 a simple, cheap and quick manner.

To provide means for rolling the barrel during transportation, the sections A and B of the barrel are provided with outwardly rolled ribs or beads 23 having tapered sides 65 24. These ribs or beads terminate at a point

adjacent the rolled edges 9 and 10 of the barrel sections, as clearly appears at 24', and extend outwardly beyond the sides of the barrel sections sufficiently far to support the barrel section and the chimes 11 away 70 from contact with the floor or ground.

So as to enable the shipment of tonnage of empty containers in freight cars, it is necessary that the sections of the containers and the heads stack or nest quite closely, 75 otherwise the car space will be utilized before the tonnage allowance of the car is loaded.

In Fig. 8, I have shown that the sections A and B will nest or stack very nicely, the 80 nesting being assisted by the chimes 11 and the tapered walls 24 of the beads 23.

In Fig. 3 of the drawings, the nesting of the barrel heads is shown, the same nesting quite closely, due to their outwardly tapered or flared side walls 17, they will slide one into the other until the bottom of one head is quite close to that of the next head below it.

My improved barrel will be preferably 90 constructed of a light weight metal, although I do not limit myself to any particular metal or material, as any suitable material can be used for the container without departing from the spirit of my invention.

In Figs. 5, 6 and 7 of the drawings, I have shown a modification of the construction used before fastening the barrel heads in the barrel.

In the construction shown in these figures 100 of the drawings, the barrel sections D and E are assembled in a similar manner as previously described in regard to the other figures of the drawings, so a description of this element of the construction will not be repeated.

The barrel sections D and E are provided at a point adjacent their ends, with an outwardly extending flange or flare 50, which is formed by bending or rolling the material of the container upon itself as clearly appears. Extending upwardly beyond the flange 50 and forming the end of the barrel sections, is a continuation 51 of the container 110 side walls.

The heads F, used to close the barrel, are composed of a bottom 52, which is slightly convex, as shown at 53 to strengthen it. Surrounding the bottom of the head are upwardly extending sides 54 having an outward taper or slant as shown, the upper ends of the sides terminating in an outward flare or approximately U-shaped roll 55, from which at a plurality of points extend 120 tongues 56.

When the barrel sections A and B are in their assembled position or form, as shown in Figs. 5 and 6 of the drawings, the heads F are dropped into the ends of the cylinder formed by the sections, the heads 130

being supported upon their upwardly flared upper edge 55, which receives the end 51 of the barrel sections. To lock the heads in position to close the container, the 5 tongues 56 are inserted through openings 57 in the flange 50 of the barrel sections and bent upwardly around and down upon this flange, as appears at 58.

To enable the barrel to be rolled, I have 10 provided barrel sections with the same outwardly rolled ribs or beads 23, having tapered or flared side walls 24, which extend outwardly beyond the sides of the barrel 15 sections sufficiently far to support the barrel section flanges 50 away from contact with the floor or ground, as has been previously described relative to the barrel construction shown in Figs. 1 to 4, inclusive.

As the shipment of tonnage of empty 20 containers in freight cars is necessary and important, the several component parts of the barrel must stack or nest quite closely, otherwise the car space will be utilized before the tonnage allowance of the car is 25 loaded, as previously described.

In Fig. 7 of the drawings, I have shown quite clearly the nesting of the barrel heads. In this figure it appears that the heads slide one into the other until the U-shaped 30 rolled upper edge of the barrel heads rest one upon the other. Although I have not shown the barrel sections D and E stacked, it will be readily understood that the same will stack and nest in a similar manner to 35 the barrel sections A and B, as is shown in Figure 8 of the drawing.

Having thus described my invention,

what I claim and desire to secure by Letters Patent is:

1. A barrel or keg or the like, comprising a body portion having an outwardly extending flare adjacent its ends, a head having extending tongues, the tongues of the barrel heads inserted within openings provided in the upper face of the body flare 45 portions, and the extending tongues adapted to be rolled backwardly upon themselves within the body flare portions for locking the heads in place to close the ends of the body. 50

2. A barrel or keg or the like, comprising a body portion having an outwardly extending flare approximately U-shaped adjacent its ends, a head for said body portion having extending tongues, the outwardly extending flare of the body portions being provided with openings in its upper face to receive the barrel head tongues, and the tongues of the barrel adapted to be inserted through said openings and to bend 60 backwardly upon themselves to lock the heads in place. 55

3. A barrel or keg or the like, comprising a body portion having an outwardly extending flare adjacent its ends, a head for 65 said body portion having extending tongues, and the tongues of the barrel heads adapted to be inserted through openings in the said flare portion to lock them in place within the flare. 70

In testimony whereof I hereunto affix my signature.

GEORGE EUGENE MITTINGER.
